UNITED STATES PATENT OFFICE.

HENRY A. HOLDER, OF LYNN, MASSACHUSETTS, ASSIGNOR, BY MESNE ASSIGNMENTS,
TO WILLIAM F. FITZGERALD, OF BROOKLINE, MASSACHUSETTS.

MACHINE FOR TREATING HIDES, SKINS, AND LEATHER.

1,261,534.

Specification of Letters Patent.

Patented Apr. 2, 1918.

Application filed November 22, 1916. Serial No. 132,891.

To all whom it may concern:

Be it known that I, HENRY A. HOLDER, a citizen of the United States, residing in Lynn, in the county of Essex and State of Massachusetts, have invented an Improvement in Machines for Treating Hides, Skins, and Leather, of which the following description, in connection with the accompanying drawings, is a specification, like characters 10 on the drawings representing like parts.

This invention relates to a machine for treating hides, skins and leather, and has for its object to provide a machine with which the major operations now performed 15 upon the hide, skin or leather by a plurality of machines of different constructions, according to the particular kind of work such as unhairing, fleshing, putting out, setting, shaving, etc., being performed, may be done 20 in a superior manner upon a single machine. To this end, the machine is provided with a bed of substantially small working area to support the work, preferably in the form of a roll of relatively small diameter, an 25 operating tool, such as a bladed cylinder to engage the work while on the bed, and a device which is movable with relation to said bed and tool to move the hide or skin away from the operator and toward the 30 bed and tool to enable the hide or skin to be worked by the tool, and then to move the treated portion of the hide or skin away from the tool and bed and an untreated portion of the hide or skin toward the said 35 bed and tool, whereby the hide, skin or leather remains under the eye and control of the operator as it is moved toward the bed roll and operating tool, and is effectively and advantageously acted upon by the 40 bladed cylinder or operating tool coöperating with the small or narrow portion of the hide or skin on the small working area of the bed roll, and further is placed and maintained under tension while the hide or skin 45 is being drawn away from the bed roll and operating tool.

The movable device to which the work is secured may and preferably will be made in the form of a drum of relatively large diameter, and it may be preferred to employ a bolster which is attached to the drum and is passed over the bed roll, which latter may and preferably will be mounted concentrically with the drum.

55 In the machine herein shown provision is

made for moving the bed roll from an inoperative into an operative position with relation to the working tool and to permit the bed roll to remain in its operative position while the movement of the drum is continued. 60

These and other features of this invention will be pointed out in the claims at the end of this specification.

Figure 1 is a front elevation of one form 65 of machine embodying this invention.

Fig. 2, a section on the line 2—2, Fig. 1, looking toward the right.

Figs. 3, 4 and 5, details in section of the drum, bed roll and working tool to illustrate 70 the operation of the machine and,

Fig. 6, a diagrammatic view to illustrate one method of moving the bed roll into its operative and inoperative positions.

In the present instance I have shown the 75 invention as embodied in one construction of machine, in which the greater portion of the machine is of known construction and substantially that shown and described in U. S. Patent No. 802,878 dated Oct. 24, 1905, 80 and known to the trade as a drum machine. The drum machine herein shown comprises essentially a segmental drum *a* of relatively large diameter and having a stationary clamping jaw 10 with which coöperates a 85 movable clamping jaw 12, carried by arms 13 mounted loosely on the shaft 14 of the drum *a*. The movable clamping jaw 12 is acted upon by a spring 15 to normally hold the said jaw against a stop 16, see Fig. 2, 90 and thereby allow the jaw 10 to move with the drum in the direction indicated by the arrow 17, Fig. 2, and away from the jaw 12 so as to open the clamp and permit a portion of the hide or skin 18 to be placed within the 95 drum and over the fixed jaw 10.

On the movement of the drum *a* in the direction indicated by the arrow 19, which may be termed its forward movement, the fixed jaw 10 is moved toward the jaw 12 100 and the hide or skin is firmly clamped between them. In the machine herein shown, the drum *a* is rotated in a forward direction indicated by the arrow 19, by a straight belt 20, see Fig. 1, which is passed about a pulley 21 on a main or driving shaft 22 and about a pulley 23 normally loose on a counter shaft 24, and said drum is rotated in the reverse direction, indicated by arrow 17, by a cross belt 25 passed about a pulley 26 on 110

the main shaft 22 and about a pulley 27 normally loose on the counter shaft 24. The pulleys 23, 27, are adapted to be rendered fast on the counter shaft 24 by clutch mechanism of known construction and comprising a sleeve 28 coöperating with clutch fingers or levers 29, 30, carried by the loose pulleys 23, 27, and adapted to be engaged with the counter shaft 24 to render the said pulleys fast thereon. The sleeve 28 is operatively connected in a known manner with a rock shaft 31 which is rocked by a lever 32. The counter shaft 24 drives the drum *a*, by a pinion 132 on the counter shaft engaging a gear 33 on a shaft 34, having a pinion 35 which meshes with a gear 36 on the drum shaft. The main shaft 22 is provided with fast and loose pulleys 37, 38, and with a pulley 39, which latter is connected by belt 40 with a pulley 41 on the shaft 42 of a bladed roll 43, which constitutes one form of operating tool. The bladed roll 43 is journaled in levers 44 pivoted at 45 to the framework of the machine and connected with a foot treadle 46 as by rods or links 47, so that the operator can bring the bladed roll into its operative position by depressing said foot treadle. The machine as thus far described is substantially such as shown in the patent above referred to. In the drum machine of the character shown in the patent referred to, the bladed cylinder 43 coöperates with the drum *a* to act on the portion of the hide or skin lying on the periphery of the drum, as the latter is rotated in its forward direction, and this machine has the advantage of carrying the hide or skin from the operator, standing in front of the machine with his foot on the treadle 46, toward and beyond the working cylinder, and leaves the portion of the hide or skin on the outside of the drum under the eye and control of the operator, who can see the condition of the hide or skin on the drum and can smooth out any plaits or wrinkles therein with his hands, so that, the hide or skin may be presented to the bladed cylinder in its proper condition to avoid cutting or otherwise injuring the hide or skin. So also on the return movement of the drum, the operator can inspect the work done by the bladed cylinder, and if the work has been improperly done in some places, the operator can cause the drum to again move forward and subject the hide or skin to a second operation without disturbing or changing the hide or skin on the drum. The drum machine presents a substantially large or wide area of surface for the bladed cylinder to work against, and for certain kinds of work it is not as efficient as those machines in which the bladed cylinder coöperates with the hide or skin while the latter is supported by a bed roll of relatively small diameter, as the bed roll presents a substantially small or narrow

area for the bladed cylinder to work on, and enables the blades of said cylinder to get into the small point of contact or narrow area of the hide or skin resting on the bed roll, and in the operation of unhairing enables the grain side of the hide or skin to be opened up, and the fine or coarse hairs to be removed, and in the operation of fleshing a smaller and cleaner cut is made. So also if small wrinkles should exist in the hide or skin, the bladed cylinder is better able to get to the bottom of the wrinkles.

So also in the rubber roll machine, the hide or skin is drawn over the bed roll by means of feed rolls of relatively small diameter, which have the effect of squeezing gelatin or valuable hide substance out of the hide. Notwithstanding the disadvantages attending the use of the rubber roll machine, it has been generally adopted by tanners for fleshing hides and skins.

The present invention has for its object to provide a machine which possesses the advantages of both the drum and rubber roll machines and none of their disadvantages, and to this end, the machine is provided with a bed roll which coöperates with the drum so that the hide or skin is left under the eye and control of the operator as it is moved toward the bladed cylinder, and coöperates with the latter to present a small working area or surface of the hide or skin for the blades to act against.

In the present instance the bed roll 50 is journaled in arms 51 mounted to turn on the drum shaft 14, and said arms are preferably made of such length that the bed roll 50 contacts with and is supported by said drum, which is of advantage as it prevents springing of the substantially long bed roll of relatively small diameter.

Provision is made for positioning the bed roll with respect to the drum *a*, so as not to interfere with the clamping of the hide or skin to the drum, and further to enable the bed roll to be moved with the drum into operative relation to the bladed cylinder, and remain in such position, while the drum continues its forward movement.

To this end, the arms 51 which carry the bed roll, are operatively connected with cams 52 located at opposite ends of the drum and herein shown as path cams, which are suitably shaped to effect movement of the bed roll from its inoperative into its operative position; be held in its operative position, and after the portion of the hide or skin outside of the drum has been acted upon by the bladed cylinder to be returned with the drum to its inoperative position.

Each path cam 52 is represented in Fig. 6 as provided with a circular portion 53 from which extend inclined portions 54, 55, and one of the inclined portions as 54 effects movement of the bed roll into its op-

erative position, and when the drum is reversed into its inoperative position, and if the drum has a continuous rotation in one direction, the other inclined portion 55 effects the return movement of the bed roll to its inoperative position.

In the present instance, the path cam 52 acts on the short arm 56 of a bell crank lever 57 whose long arm 58 has a pin and slot 60 connection with the arm 51 supporting the bed roll at one end, the long arm 58 carrying a pin 59 which is extended into a slot 60 in the arm 51, which slot is arranged to enable the pin to turn the arm 51 so as to 15 raise the bed roll from its inoperative position indicated by full lines in Fig. 6 and in Fig. 3 into its operative position represented by dotted lines in Fig. 6 and in Fig. 4, in which latter position the bed roll is in 20 operative relation to the bladed cylinder. It may be preferred to provide a bolster 62 of known construction for the bed roll 50 and the drum *a* upon which the hide or skin 18 rests, and in the present instance, the bolster 25 62 has one end fastened to the stationary jaw 10 of the drum and is passed over the bed roll and has its other end yieldingly secured by springs 63 to the drum.

The cam 52 may be driven from the drum 30 shaft 14 by a gear 64 on the drum shaft, meshing with an intermediate gear 65, which meshes with a gear 66 fast to the path cam 52. The operation of the machine herein shown may be briefly described as follows: Assume the drum and bed roll in their 35 inoperative positions represented in Fig. 3. The operator at the front of the machine throws one half of the hide or skin 18 into the drum and then moves the clutch lever 32 40 to start the drum rotating in the direction of the arrow 19. As the drum is moved toward the bladed cylinder 43, the bed roll 50 is moved simultaneously with it toward the bladed cylinder, until the bed roll has 45 been brought into its operative position with relation to said cylinder as represented in Fig. 4. On the movement of the drum toward the bladed cylinder, the fixed jaw 10 picks up the movable jaw 12 and the 50 hide or skin is firmly clamped or secured to the drum. When the bed roll has been brought into its operative position, the operator depresses the treadle 46 and brings the bladed cylinder into engagement with 55 the portion of the hide or skin resting on the bed roll, and as the drum continues its forward movement in the direction indicated by the arrow 19, and as represented in Fig. 5, the hide or skin is carried with it away 60 from the bed roll and bladed cylinder and the latter performs its work, which may be unhauling, fleshing, putting out or stretching, scudding, shaving, etc., depending upon the character of the blades or vanes in the 65 working cylinder 43. On the movement of

the drum *a* beyond the operative position of the bed roll, the portion of the hide or skin on the bolster or outside of the drum is moved away from the operator toward the bladed cylinder, but remains under his eye 70 and control, so that, he is enabled to smooth out the hide or skin on the bolster and arrange it so that it may be presented to the bladed cylinder in the best possible condition, and if the hide or skin is in such condition that it cannot be properly smoothed out by the operator, he has it in his power 75 to reverse the machine and replace the hide or skin.

When the clamped end of the hide or 80 skin is drawn away from the bed roll and placed under tension by the drum coöperating with the bed roll and working cylinder, the grain side in the operation of unhauling is opened up fully in the small area of that 85 portion of the hide or skin which is engaged with the narrow working area of the bed roll, assisted by the tension or pull upon the hide by the drum and clamps, and as a result the fine or coarse hairs, dirt or other 90 foreign matter are removed by the blades of the working cylinder, which blades act on practically a point of contact with the hide or skin or what may be designated a surface area of narrow width, which is ex- 95 tended lengthwise or axially of the bed roll. If fleshing and shaving are being done, the small clean cut of the rubber roll machine is obtained. If putting out, stretching or like operations are being performed, they 100 are effectively performed as the work is presented to the bladed cylinder under the eye and control of the operator, and the body portion of the hide or skin can be put out, stretched, etc., and the machine can 105 then be returned to its starting position and the hide or skin shifted and clamped in its shifted position so as to present the shanks in proper position to be effectively treated.

It will therefore be seen, that with a machine embodying this invention, the operations of fleshing and unhauling which are now performed on the rubber roll machine, such for instance as shown and described in U. S. Patent No. 696,588, dated April 1, 110 1902 can be performed, and that the operation of putting out, stretching, etc., which are now performed on the so-called single table and serial table machines, such for instance as shown in U. S. Patents No. 115 274,858, dated Mar. 27, 1883, and No. 722,888 dated March 17, 1903, can be performed, and the operation of shaving which is now commonly performed on machines of the character shown and described in U. S. 120 Patent No. 618,620, dated Jan. 31, 1899 can be performed on this machine with advantages not possessed by the individual machines referred to.

For fleshing and unhauling, a machine 130

4
embodying the present invention has the additional advantages of having the hide or skin under the eye and control of the operator; the advantage of retaining the gelatin and other valuable substances in the hide or skin; the further advantage of being able to repeat the operations on the return movement of the hide and also repeat the operations on a second forward movement without removing the hide or replacing the same in the machine, and the still further advantage in the operation of unhairing of a greater opening up of the pores of the hide or skin, because of the tension on the hide or skin placed upon it by the clamp which is located at a lower level than the bite of the bed roll and working cylinder.

For putting out, stretching and like operations the advantages of having the hide or skin under the eye and control of the operator are retained, and the additional advantages of the small area of contact of the blades of the cylinder on the hide or skin, and of the treated portion of the hide or skin being maintained under tension between the clamp and the bed roll and working cylinder, are obtained, with the result, that the wrinkles, water, scud, etc., are removed in a superior manner, while leaving the untreated portion of the hide or skin, which is approaching the bladed cylinder and bed roll, loose and free to respond to the working out movement of the helical bladed cylinder.

Furthermore for putting out, stretching, etc., it has the advantage of the single or serial table putting out machines, in that the hide or skin after passing the operating tool is kept under tension until the whole portion of the skin being worked has passed the operating tool, and it has the further advantage that the hide or skin can be placed in any position on the drum and retained in this position against any pull of the working tool, and as a result the shank portions of the hide or skin can be put out, set out, etc., just as well as the body portion, and thereby dispense with the use of separate machines now commonly used for working out the shanks separate from the machines employed for putting out, stretching, setting out, etc., of the body portions. In the present instance, the drum constitutes one form of movable device which carries the hide or skin from one side of a plane through the operating tool to the other side thereof, and while it may be preferred to use the drum for this purpose, it is not desired to limit the invention in this respect.

So also it may be preferred to use a bolster which is secured to the drum and passed over the bed roll as herein shown, but it is not desired to limit the invention in this respect.

In the present instance only sufficient

parts of the drum machine have been shown to enable the operation to be understood as the portion of the machine is substantially the same as that shown in the Patent No. 802878 above referred to.

In the present instance one construction or form of machine embodying the invention is shown, but it is not desired to limit the invention to the particular construction shown.

Claims.

1. In a machine of the character described, in combination, a drum, means for rotating it, a bed roll coöperating with said drum, a bolster secured to the drum to move therewith and extended over the bed roll, means for securing a hide or skin to the drum to move therewith and effect bodily movement of the hide or skin with relation to said bed roll, means for moving said bed roll into its operative position and means for holding the bed roll in said operative position while permitting movement of said drum in a reverse direction, and a bladed cylinder coöperating with said bed roll to act on the hide or skin as it is being bodily moved with relation to said bed roll by said drum.

2. In a machine of the character described, in combination, a drum, means for rotating it, a bed roll coöperating with said drum, means for securing a hide or skin to the drum to move therewith and effect bodily movement of the hide or skin with relation to said bed roll, means for positively moving said bed roll into its operative position and for holding it in said position uninfluenced by reverse movement of said drum, and a bladed cylinder coöperating with said bed roll to act on the hide or skin as it is being bodily moved with relation to said bed roll by said drum.

3. In a machine of the character described, in combination, an operating tool, a bed roll coöperating therewith to support the hide or skin while it is being acted upon by said tool, a support to which the hide or skin is secured, said support being movable with relation to the operating tool to carry the hide or skin over the bed roll and toward the operating tool to enable the hide or skin to be treated by the operating tool, and to carry the hide or skin in the same direction away from the operating tool after it has been treated thereby, and a cam to move said bed roll into its operative position and to hold it against movement while in said operative position.

4. In a machine of the character described, in combination, a bladed cylinder, a bed roll for the hide or skin with which said bladed cylinder coöperates and movable into operative relation to said bladed cylinder, a drum to which said hide or skin is secured, said drum being movable with relation to said bladed cylinder to carry the hide or

- skin from a position on one side of a plane through the bed roll in the operative position of the latter, toward said plane, to bring the hide or skin into working position with relation to the bladed cylinder, and then carry the hide or skin beyond said plane to draw the hide or skin over the bed roll away from the bladed cylinder, while the latter is acting upon the portion of the 5 hide or skin in engagement with said bed roll, and means for holding said bed roll in its operative position against movement by the drum or the work thereon.
5. In a machine of the character described, 15 in combination, an operating tool, a bed roll for the hide or skin with which said operating tool coöperates and movable into its operative position, a drum to which said hide or skin is secured, said drum being 20 movable in opposite directions with relation to said operating tool, means for moving said bed roll into its operative position, and means for retaining it in said position for a portion of the reverse movement of 25 said drum.
6. In a machine of the character described, 30 in combination, a tool to work upon the hide or skin, a bed of substantially small working area for the hide or skin to engage and with 35 which said tool coöperates, a support for the hide or skin movable with relation to said bed and tool to carry the hide or skin to the said tool, and enable the latter to work upon the hide or skin, and then carry 40 the treated portion of the hide or skin away from the said tool while said support is moving in the same direction to present an untreated portion of the hide or skin to the said tool, means for securing said hide or skin to said support, means for moving said support, means for moving said bed into its operative position, and means for 45 locking it in its operative position to permit the said support to be reversed with the said bed in its operative position.
7. In a machine of the character described, 50 in combination, a bed of substantially small working area for the hide or skin to engage, an operating tool coöperating therewith, a device to which a hide or skin is secured, said device being movable with relation to said bed and tool to move a hide or skin away from the operator and toward the tool and bed to enable the hide or skin to be worked by the said tool, and then to 55 move the treated portion of the hide or skin away from the tool and bed and an untreated portion of the hide or skin toward the said tool and bed, and a rotatable cam coöperating with said bed to effect movement thereof into its operative position and to hold it in said operative position while said device is moving in a reverse direction.
8. In a machine of the character described, 60 in combination, an operating tool, a bed of substantially small working area for the hide or skin to engage, said bed being movable into operative and inoperative relation to said tool, a device to which a hide or skin is secured, said device being movable simultaneously with the bed toward the operating tool and being capable of further movement in the same direction while the bed remains in its operative position with relation to said tool, means for moving said device, and means for holding said bed in its 65 operative position to permit the said device to be moved forward or backward at the will of the operator with the said bed in its 70 operative position.
- 80 In testimony whereof, I have signed my name to this specification.
- HENRY A. HOLDER.

Copies of this patent may be obtained for five cents each, by addressing the "Commissioner of Patents, Washington, D. C."
